UNITED STATES PATENT OFFICE.

WINTHROP L. JACOBS, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 13,799, dated March 20, 1883.

Application filed January 25, 1883. Term of patent 3½ years.

To all whom it may concern:

Be it known that I, WINTHROP L. JACOBS, of East Orange, Essex county, New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The face of the design is irregularly traversed by an open net-work of angular stems

bearing, variously disposed along their length, the flowers A, B, and C, and various smaller leaf, flower, and gem shapes, as is clearly shown in the photograph.

I claim—

The design for a carpet, consisting of the flowers A, B, and C, and the smaller leaf, flower, and gem shapes, and the connecting angular stems, substantially as shown and described.

WINTHROP L. JACOBS.
